[57] CLAIM

The ornamental design for a key mounted flashlight, as shown and described.

DESCRIPTION

FIG. 1 is a front elevational view of a key-mounted flashlight showing my new design;

FIG. 2 is a top plan view;

FIG. 3 is a left side elevational view;

FIG. 4 is a right side elevational view;

FIG. 5 is a rear elevational view;

FIG. 6 is a bottom plan view;

FIG. 7 is a top perspective view;

FIG. 8 is a bottom perspective view; and

FIG. 9 is an enlarged bottom perspective view with the key shown in broken lines being for illustrative purposes only and not part of the claimed design.
